COMB

Application filed May 8, 1930. Serial No. 450,804.

The present invention relates to improvements in devices for treating the hair and the primary object of the invention is to provide an improved comb for applying a solution to the hair thru the process of combing the hair.

A further object of the invention is to provide an improved comb adapted to be used for straightening hair thru the depositing of a solution contained within a chamber provided in the comb.

A further object resides in the novel construction whereby feeding of the solution to be applied to the hair is brought about thru capillary action and thus maintaining an even escape of the solution without requiring valves or other fluid control means to be operated by the user.

A still further object resides in the novel arrangement whereby the liquid applicator is readily and easily removable from the comb proper to permit ready and thorough cleansing of the device and use of the comb without the applicator.

Other objects and advantages of the invention will be apparent during the course of the following detailed description, taken in connection with the accompanying drawings forming a part of this specification and in which drawings:

Figure 1 is a side elevation of the improved hair treating device.

Figure 2 is a view in side elevation showing the applicator removed and fragmentary portions of the comb body broken away for illustrating certain details of construction.

Figures 3 and 4 are sectional views taken on the respective lines in Figure 1.

Figure 5 is a side elevation of a slightly modified form of comb.

Figures 6 and 7 are sectional views on the respective lines in Figure 5.

In the drawings, like reference characters designate corresponding parts thruout the several views.

Referring first to the form of invention shown in Figures 1 to 4 inclusive, the improved comb comprises an elongated hollow stock or shank 5 of oval shape in cross section and providing a liquid chamber 6 which

is also preferably oval shaped. The liquid chamber 6 is closed at the forward end of the stock and at the rear end of the stock may be rounded and internally threaded for threaded reception of a closure plug 7 which when removed permits filling of the chamber with a liquid adapted to be applied to the hair. The improved device is intended for use in straightening hair and the chamber 6 preferably receives an alkaline solution.

The stock may be slightly arched longitudinally and is provided along its lower edge for a portion of its length from the forward end with a series of tapering comb teeth 8 forming a comb portion at the forward end of the stock. The portion of the stock extending rearwardly from the comb portion forms a handle to be grasped by the user.

Opening thru one side of the stock above the teeth of the comb portion and communicating with the chamber 6 is a series of relatively small feed or liquid escape openings 9. These openings are preferably arranged at an incline and communicate with the bottom of the chamber 6 with the outer ends of the apertures opening into somewhat of a channel formed along the device directly above the juncture of the teeth with the stock as indicated at 10 in Figure 3.

The stock and teeth are preferably formed as an integral structure and are preferably molded from a material such as hard rubber or some similar non-metallic material.

Referring now to the applicator means for depositing the solution upon the hair during combing, the same is adapted to be removably associated with the comb portion 8. Extended thru the stock 5 adjacent opposite ends of the comb portion and spaced above the series of apertures 9 are two mounting studs 11 having threaded outer ends for threaded reception of preferably knurled clamping nuts 12. These mounting studs 11 as will be observed in Figure 4 project from that side of the stock thru which the apertures 9 open. Adapted to be positioned at its upper edge over the projecting ends of the studs 11 is a distributor pad 14 formed of an absorbent material such as felt or the like. This distributor pad may have its ends aper-

tured for positioning over the studs 11 and is of such width as to have its lower edge extend for about one half of the length of the comb teeth. The pad is of a length slightly less than the length of the comb portion and as will be observed in Figure 3 extends over the apertures 9 so that liquid within the chamber 6 when passing thru the apertures will be absorbed by the pad. The distributor pad 14 is held in engagement with the comb teeth by means of a clamp plate or strip 15 formed of hard rubber or some such similar material. This clamping plate 15 has apertures along its upper edge for positioning over the mounting studs 11 and is held in position against the pad by the clamping nuts 12. This clamping of the pad 14 along its upper edge portion will prevent the solution from working upwardly as will readily be apparent by observing Figure 3. The plate 15 is of slightly less width than the pad 14 so that the lower edge of the pad projects slightly below the lower edge of the clamping plate and permits the pad to readily contact with the hair during the combing operation.

With the apertures 9 opening along the channel or groove 10 it will be seen that when the distributor pad is clamped firmly against the stock 5 the material of the pad will not be so compressed at a point along the row of apertures as to prevent ready capillary action of the liquid in moistening the pad.

As an illustration of using the device for straightening hair, the plug 7 is first removed and the chamber 6 filled with the alkaline solution and after which the filler end of the chamber is sealed by the plug. Escape of the solution thru the apertures 9 will then take place thru capillary action and thoroughly pregnate the absorbent pad 14 with the solution. The comb is now ready for use and by drawing the comb thru the hair with the side of the comb carrying the pad, away from the scalp, a certain amount of the solution is deposited on the hair by the distributor pad. During use of the comb a certain amount of heat will be produced thru friction and this heat will be sufficient to vaporize the solution so as to thoroughly cover the hair. The operation may be repeated as found necessary and at times to take care of the new growth of hair.

Referring now to the form of comb shown in Figures 5, 6 and 7, an arrangement is herein shown whereby the mounting studs 11 and clamping bolts 12 as previously described may be dispensed with and the clamping plate attached by means of a sliding interlocking fit with the stock. The stock or shank 5' is of hollow formation to provide the liquid chamber 6' closed at its rear end by the closure plug 7'. Provided adjacent the forward end of the stock 5' is the comb portion 8' provided with the enlarged terminal teeth 20.

Opening thru one side of the stock along the upper portion of the comb 8' and communicating with the chamber 6' is the series of feed openings or apertures 21. Formed along one side of the oval shaped stock 5' above the series of apertures 21 is a flange 22 forming an abrupt downwardly facing shoulder. A distributor pad 14' is adapted to be disposed over one side of the comb portion and held in position by the sliding clamp plate or strip 25.

The plate 25 at each end is provided with inwardly extending flanges as shown in Figure 7 and these flanges are each provided with dove tailed grooves 26 extending from the upper to the lower edges of the plate. Formed beneath each end portion of the flange 22 and extending along the sides of the enlarged end teeth 20 are dove-tailed tenons 28 which are received in the grooves 26 when the clamping plate is slid into position in abutting engagement with the lower edge of the flange 22. As will be observed in Figure 6, sliding of the clamping plate 25 into position will firmly grip the upper portion of the distributor pad 14 between the upper portion of the plate and the side of the stock. This method of detachably mounting the clamping plate permits of the plate and stock being formed of a non-metallic material such as hard rubber or the like. The wedging of the upper portion of the distributor pad will prevent ready downward sliding of the plate, and during use the plate will be normally urged to a position against the flange 22.

In both forms of the invention it will be seen that the flat clamping plate holds the distributor pad in a proper relation against one side of the comb teeth and in such relation to the stock as to permit ready escape of the solution thru capillary action. It will also be noted that the liquid escape apertures open thru one side of the device above the comb teeth and in such relation to the tightly compressed portions of the distributing pad as to permit proper feeding of the liquid.

From the foregoing description it will be apparent that a novel and efficient device of this character has been disclosed embodying an arrangement whereby the distributing pad is efficiently pregnated with the solution for depositing of the solution upon the hair during a combing operation. It will also be apparent that an improved hair treating device of this nature has been disclosed embodying an arrangement whereby the distributing pad is moistened thru capillary action.

Changes in detail may be made to the forms of invention herein shown and described, without departing from the spirit of the invention or the scope of the following claims.

I claim:

1. A device of the class described comprising an elongated hollow body portion providing a liquid chamber, means for closing one end of the chamber, a series of apertures arranged longitudinally of the body portion in communication with the chamber and opening at one side of the body, comb teeth projecting from the body below the row of apertures, a distributor pad of absorbent material overlying the apertures and a portion of the comb teeth, and retaining means for the pad. 5
2. A device of the class described comprising an elongated hollow body portion providing a liquid chamber, means for closing one end of the chamber, a series of apertures arranged longitudinally of the body portion in communication with the chamber and opening at one side of the body, comb teeth projecting from the body below the row of apertures, a distributor pad of absorbent material overlying the apertures and a portion of the comb teeth and a removable clamping 10 plate for the pad. 25
3. A device of the class described comprising an elongated hollow body portion providing a fluid chamber, a filler opening for the chamber, closure means for the filler opening, a series of apertures arranged longitudinally of the body portion and opening at one side thereof, comb teeth extending from the body portion below the row of apertures, a pad of absorbent material overlying the apertures and a portion of the comb teeth, a flat clamping plate for the pad, and retaining means for the clamp plate and compressing the upper edge of the pad against the side of the hollow body portion 30 above the row of apertures. 35
4. A comb of the class described comprising a hollow stock being closed at its forward end, said stock providing a fluid chamber, closure means for the rear end of the chamber, a comb portion embodying teeth projecting from the forward portion of the stock, a series of feed apertures opening thru the side of the stock above the comb teeth, an absorbent pad arranged over the feed 40 apertures and overlying a portion of the comb teeth, a clamp plate disposed over the outer side of the pad, and means releasably retaining the plate in clamping relation over the outer side of the pad whereby the pad is held in position over the feed apertures and against the side of the comb teeth. 50
5. A comb of the class described comprising an elongated hollow stock providing a fluid chamber closed at the forward end of the stock and open at the rear end of the stock, a closure means for the rear end of the chamber, a comb portion at the forward end of the stock, a series of feed openings arranged longitudinally of the stock above the 55 comb portion and communicating with said
- chamber, said feed openings opening thru the lower side portion of the stock, a pad of absorbent material arranged over the feed openings and overlying a portion of the comb, and means for tightly clamping the upper portion of the pad against the stock above the feed openings and retaining the lower portion of the pad in light bearing contact with the comb. 70
6. A comb comprising an elongated hollow stock of oval shape in cross section and providing a chamber closed at the forward end of the stock, removable closure means for the rear end of the chamber, a comb portion at the forward end of the stock providing a channel along the lower side portion of the stock, a series of feed openings for the chamber and opening along the channel, an absorbent pad disposed over the feed openings with its upper portion overlying one side of the stock and its lower portion overlying a portion of the comb teeth, and a removable clamp plate disposed over the outer side of the pad for retaining the pad in position and its upper edge portion in a tightly compressed condition against the side of the stock. 75
7. A comb comprising an elongated hollow stock of oval shape in cross section and forming a fluid chamber closed at the forward end of the stock, closure means for the rear end of the chamber, a comb portion provided at the forward end of the stock, a series of feed openings for the chamber and opening thru one side of the stock in slightly spaced relation above the teeth of the comb portion, a pad of absorbent material disposed over the feed openings and overlying a portion of the comb teeth, a flat clamping plate disposed over the outer side of the pad, and attaching means at 80 each end of the plate for firmly compressing the upper portion of the pad against the side of the stock above the feed openings. 85
8. A comb comprising a hollow stock providing a fluid chamber closed at the forward end of the stock, a closure plug for the chamber and threaded into the rear end of the stock, a comb portion at the forward end of the stock embodying wedge-shaped teeth, said stock having a channel formed therealong 90 at one side immediately above the comb teeth, a series of feed openings for the chamber and opening along the channel, a distributor pad of absorbent material disposed over the series of feed openings and extending above 100 and below the openings, a clamping plate disposed over the outer side of the pad, and means for detachably retaining the plate in position. 105
9. A comb comprising an elongated hollow stock providing a liquid chamber closed at its forward end and having a filler opening at its rear end, closure means for the filler opening, a comb portion provided at the forward end of the stock, a series of feed open- 110
- 125
- 130

ings for the chamber and opening thru one side of the stock above the comb portion, mounting studs projecting laterally from the stock above the feed openings, an absorbent pad supported at its upper edge upon the stud, and extending over the feed openings and a portion of the comb teeth, a clamping plate removably supported by the studs at the outer side of the pad, and clamping screws 10 threaded upon the studs for retaining the plate in operative relation at the outer side of the pad.

10. A comb comprising a hollow stock providing a chamber closed at the forward end 15 of the stock and having a filler opening at the rear end of the stock, closure means for the filler opening, comb forming teeth depending from the forward portion of the stock, a series of feed openings for the chamber and 20 opening thru one side of the stock above the comb teeth, threaded mounting studs projecting laterally from the stock adjacent each end of the comb teeth, a distributor pad of absorbent material supported at its upper edge 25 upon the studs to extend over the feed openings and a portion of the comb teeth, a flat clamping plate supported at its upper edge on the studs in engagement with the outer side of the pad, and a clamping screw threaded 30 upon each stud into engagement with the plate for firmly compressing the upper edge of the pad against one side of the stock above the feed openings.

11. A comb comprising a hollow stock providing a liquid chamber closed at the forward end of the stock and having a filler opening at the rear end thereof, closure means for the filler opening, a flange formed along one side of the stock adjacent the forward end thereof, a series 40 of feed openings for the chamber and opening thru one side of the stock below the flange, comb teeth depending from the stock below the feed openings, a distributor pad disposed over the feed openings, and a retaining plate for the pad and means for interlocking said retaining plate with the end comb teeth.

12. A comb comprising an elongated hollow stock providing a chamber closed at the forward end of the stock and having a filler opening at the rear end thereof, closure means for the filler opening, a flange formed along one side of the stock adjacent the forward end thereof, a comb portion beneath the 55 forward end of the stock embodying enlarged end teeth, a series of feed openings for the chamber and opening thru one side of the stock above the comb teeth and between the enlarged end teeth of the comb, a pad of 60 absorbent material disposed over the feed openings with its upper portion extending to said flange and its lower portion overlying a portion of the comb teeth, a dove tailed tenon formed along each end comb tooth 65 beneath said flange, and a clamping plate

having dove tailed grooves at each end thereof for sliding interlocking engagement with said tenons whereby the pad is held in position and against displacement from over the feed openings.
